UNITED STATES PATENT OFFICE

EDWARD W. CARPENTER, OF FAIRFIELD, CHARLES LA REAU, OF BRIDGEPORT, AND HENRY MORGAN KELLOGG, OF STRATFORD, CONNECTICUT, ASSIGNORS TO THE E. W. CARPENTER MANUFACTURING COMPANY, OF BRIDGEPORT, CONNECTICUT, A CORPORATION OF CONNECTICUT

SHADE HOLDER

Application filed June 15, 1931. Serial No. 544,352.

This invention relates to new and useful improvements in lamp shade holders of the type including means to resiliently grip an electric light bulb whereby to support the shade from the bulb.

An object of the invention is to provide an improved shade holder wherein the resilient bulb gripping loops are mounted or secured in a positive and economical manner, and one which is not liable to break or become loosened.

A further object is to provide a lamp shade holder including a mounting plate or member having portions pressed upwardly therefrom, and resilient loops each formed from a length of material and having their ends extending laterally and passed beneath the portions of the mounting member and secured to the mounting member by pressing said portions downwardly against the end portions of the loops.

Another object is to provide a shade holder as stated and wherein the plate or mounting member has ears or lugs lanced and pressed therefrom and over which metal parts of a shade may fit to prevent the shade slipping off the holder.

Other objects and advantages will become apparent from a consideration of the following detailed description taken in connection with the accompanying drawing wherein an embodiment of the invention is shown. However it is to be understood that the invention is not limited to the details shown but includes all such variations and modifications as fall within the spirit of the invention and the scope of the appended claims to which claims reference is to be had for a definition of the invention.

In the drawing:

Fig. 1 is a central sectional view showing the improved holder in position and mounting a shade on a bulb;

Fig. 2 is a view at right angles to Fig. 1, the shade being omitted and the bulb being shown by dotted lines;

Fig. 3 is a bottom plan view of the improved shade holder; and

Fig. 4 is a perspective view of the same. Referring in detail to the drawing and

first particularly to Fig. 1, the shade holder of the present invention is there shown in position mounting a shade 5 on a bulb 6. The improved holder includes a plate or mounting member 7 carrying a pair of loops 8 and 9 projecting from one side thereof and having a threaded nipple or stud 10 secured to and projecting from the other side thereof. This stud may be secured to the plate by providing it with a flange 22 to rest on top of the plate and riveting over the lower end 23 on the under side of the plate. It has been old to spot weld the resilient arms to the plate 7 but this has been very unsatisfactory as the welding frequently breaks and in addition no matter whether or not a tempered wire is used the heat from the welding anneals the wire at that point and it becomes a soft wire so that when it is spread apart over a bulb it takes a set and does not hold on readily.

According to the present invention the loops or resilient bulb gripping members 8 and 9 are secured to the plate or mounting member 7 in an improved manner which does not require soldering or welding. A pair of strap-like portions 14 and 15 are lanced and pressed from the plate 7. Each of the loops 8 and 9 is formed from a single length of resilient wire bent to provide the loops and then having its end portions extending in opposite directions as at 16 (see Fig. 4) and then bent substantially at right angles to extend laterally of the loops as at 17.

In mounting the loops 8 and 9 on the plate or mounting member 7 the laterally extending ends 17 of the loops or of the wires forming the loops are passed under the pressed up strap-like portions 14 and 15 from opposite sides as most clearly shown in Figs. 3 and 4. That is, the laterally extending end portions 17 of the loop 8 are inserted under the strap-like portions 14 and 15 from one side and the laterally extending end portions 17 of the loop 9 are extended under the strap-like portions from the opposite side.

After the end portions are disposed as stated pressure is applied to the portions 14 and 15 in a manner to press these portions against the laterally extending ends of the loops whereby to securely clamp the portions

17 and therefore the loops to the plate or member 7. It will be appreciated that this method of fastening or anchoring the loops does not require the use of heat and therefore if the loops are made of tempered wire they will not become annealed due to the manner in which they are secured. That is spot welding and the like is not necessary. It will also be apparent that the loops may be readily and quickly secured to the plate or mounting member 7 and that in securing the loops no action is taken which would damage or injure the loops in any manner, and they retain their original resilient condition.

The plate or member 7 is also treated to provide a means adapted to cooperate with the metal part of a shade so as to prevent the shade slipping off the holder. To this end, spaced ears 18 are lanced or pressed from the plate to project from the upper side thereof as shown. It will be appreciated that the material forming the ears 18 may be lanced from the plate 7 at the same time that the material for the strap-like members 14 and 15 is lanced. The material forming the ears 18 is of course, displaced from the plate in a direction opposite to that in which the material forming the strap-like portions 14 and 15 is displaced. A common way of mounting the shade is by means of wires 19 secured to a ring or plate 11 which also has a central circular portion 20 threaded to screw onto the shell of a lamp socket. The lugs 18 are so spaced as to fit with this central portion as shown so that the shade and its holder are effectively held against lateral movement on the member 7. The device is often used this way but it is preferred to clamp the member 11 in this position. This can be readily done by means of a plate 12 having an opening to slip over the stud 10 and a downwardly extending flange 21 to rest on top of member 11. The plate 12 can be clamped by a nut 13 so that the member 11 is securely clamped to the plate 7.

Having thus set forth the nature of our invention, what we claim is:

1. In a lamp shade holder, a mounting member, a pair of looped clamping members to engage over a bulb, said mounting member having a pair of portions pressed therefrom, each of said loops formed of a length of wire having its end portions extending laterally of the loop, and said laterally extending end portions disposed beneath the said pressed-up portions of the mounting member and securing the loops to the mounting member.

60 2. In a lamp shade holder, a mounting member, a pair of looped clamping members to engage over a bulb, said mounting member having a pair of portions pressed outwardly therefrom, said loops formed each of a length of wire having its end portions extending

laterally of its loop, and said end portions of the respective wires passed beneath said outwardly pressed portions of the mounting member and in opposite directions and securing the loops to the member.

3. In a lamp shade holder, a mounting member, a pair of looped clamping members to engage over a bulb, said mounting member having a pair of portions pressed outwardly therefrom, and said loops formed each of a length of wire and each having an end portion passed beneath each of the outwardly pressed portions of the mounting member and clamped to the mounting member by pressing said portions of the mounting member against said end portions of the wires. 75 80

4. A shade holder comprising a mounting member, a pair of strap-like portions carried by said mounting member at one side thereof, said strap-like portions arranged substantially diametrically opposite one another, a pair of loop members, said loop members each formed of a length of wire bent to form a loop and then having its ends extending laterally of the loop and parallel to one another and in the same direction, one of said loop members having its respective end portions disposed beneath said strap-like portions and extending in one direction, and the other of said loop members having its respective parallel end portions disposed beneath said strap-like portions and extending in the opposite direction. 95

5. A shade holder comprising a mounting member, a pair of strap-like portions carried by said mounting member at one side thereof, a pair of loop members, said loop members each formed of a length of wire bent to provide a loop and then having its ends extending in opposite directions and then bent to extend laterally of the loop and parallel to one another and in the same direction, one of said loop members having its respective parallel end portions disposed beneath said strap-like portions and extending in one direction, and the other of said loop members having its respective parallel end portions disposed beneath said strap-like portions and extending in the opposite direction. 100 105 110 115

6. A shade holder comprising a mounting member, a pair of strap-like portions carried by said member at one side thereof, a pair of loop members, said loop members each formed of a length of wire bent to provide a loop and then having its ends extending laterally of the loop and parallel to one another, said loop members having their respective parallel end portions clampingly engaged by said strap-like portions to secure said loops to said mounting member, said loops arranged laterally of said strap-like portion, and said parallel end portions clamped intermediate their ends whereby said loops are yieldable toward and from one another. 130

7. A shade roller comprising a mounting member, strap-like portions carried by said mounting member at one side thereof, a pair of loop members, said loop members each 5 formed of a length of wire bent to provide a loop and then having its end portions extending laterally of the loop and substantially parallel to one another, said loop members having their end portions clampingly 10 engaged by said strap-like portions to secure said loops to the mounting member, said loops arranged laterally of said strap-like portions, and said end portions of the loops clamped intermediate their ends whereby the 15 loops are yieldable toward and from one another.

In testimony whereof we affix our signatures.
